COUNTERLINER FOR SHOES

Filed Aug. 4, 1926

FIG. 1.

FIG. 2.

Inventor:

J. D. Langdon
Monroe Miller

By

Attorney.

UNITED STATES PATENT OFFICE.

JESSE D. LANGDON, OF LOS ANGELES, CALIFORNIA.

COUNTERLINER FOR SHOES.

Application filed August 4, 1926. Serial No. 127,100.

The present invention relates to counter liners for shoes, slippers, and similar articles of footwear, and aims to provide a novel and improved device of that kind.

5 Another object of the invention is the provision of a counter liner having at its upper edge a depending apron to be disposed on the exterior of the counter of the shoe in order to effectively retain the counter 10 liner in place as well as providing an ornamental appearance of the shoe.

With the foregoing and other objects in view, which will be apparent as the description proceeds, the invention resides in the 15 construction and arrangement of parts, as hereinafter described and claimed, it being understood that changes can be made within the scope of what is claimed, without departing from the spirit of the invention.

20 The invention is illustrated in the accompanying drawing, wherein—

Figure 1 is a perspective view of a counter liner embodying the improvement.

Fig. 2 is a cross section of the counter 25 portion of a shoe showing the liner in place.

The counter liner 3 may be of any suitable construction and of leather or other suitable material to be disposed within the counter of an Oxford shoe, slipper, or the like, and 30 such liners are well known.

The improvement consists in using an apron or flap 5 at the exterior of the upper edge portion of the counter liner 3, with stitching 6 or other securing means along 35 the upper edge of the apron 5 to hold said apron in place close to the liner 3. The apron 5 may be of the same material as the liner 3 or of different material, and may be a separate piece sewed on the liner, or may 40 be an extension of the liner folded down.

When the liner 3 is positioned within the counter 4 of the shoe, the apron 5 extends down on the exterior of the counter along the upper edge thereof, thereby supporting 45 the liner 3 in place within the counter and preventing the liner from being forced down

out of position when the heel of the foot slips down into the counter. The apron or flap 5 also presents an ornate appearance, and will prevent the liner from creeping 50 down in the shoe. The liner will therefore remain in place in order to prevent chafing of the heel of the foot.

The stitching 6 secures the apron 5 directly against the exterior surface of the liner 3, thereby holding the apron close to the liner so as to bear under pressure against the exterior surface of the shoe when the liner is applied thereto. The stitching 6 is located above the upper edge of the shoe, 60 with the upper edges of the liner 3 and apron 5 extending upwardly above the stitching and bearing directly together. By this construction the upper edge portion of the shoe will be gripped tightly with a 65 wedging action immediately below the stitching 6 between the liner 3 and apron 5.

Having thus described the invention, what is claimed as new is:—

A counter liner for an Oxford shoe, slipper, or similar article of footwear adapted to fit within the counter of the article and of a slightly greater height than the counter so that its upper edge portion extends slightly above the upper edge of the counter, a depending exterior apron extending along the upper edge portion of the liner to overlap said counter on the exterior thereof with the upper edge of the apron extending slightly above the upper edge of 80 said counter, the upper edge portions of the liner and apron having their adjacent surfaces bearing together snugly, and stitching extending through the upper edge portions of said liner and apron to secure them directly together, so that the liner and apron are held snugly against the inner and outer surfaces of the counter. 85

In testimony whereof I hereunto affix my signature.

JESSE D. LANGDON.
